COMBINED PENCIL POINTER AND DUST RECEIVER

Lawrence E. Blazey, 537 Juneway Drive,
Bay Village, Ohio

Filed June 29, 1960, Ser. No. 61,156

Term of patent 7 years

(Cl. D74—21)

FIG. 1

FIG. 2

FIG. 3

FIG. 4

FIG. 5

FIG. 1 is a top perspective view of a combined pencil pointer and dust receiver showing my new design;

FIG. 2 is an end elevational view thereof as seen from the right of FIG. 1;

FIG. 3 is a top plan view thereof as it appears with the dust receiver in disengaged position;

FIG. 4 is a side elevational view thereof; and

FIG. 5 is an end elevational view as seen from the left of FIG. 1.

I claim:

The ornamental design for a combined pencil pointer and dust receiver, substantially as shown.
